UNITED STATES PATENT OFFICE.

DAVID G. McCAA, OF PALO ALTO, CALIFORNIA, ASSIGNOR OF ONE-HALF TO CORNELIUS D. EHRET, OF PHILADELPHIA, PENNSYLVANIA.

SIGNALING METHOD AND APPARATUS.

1,423,345.

Specification of Letters Patent.

Patented July 18, 1922.

Application filed May 20, 1921. Serial No. 471,142.

To all whom it may concern:

Be it known that I, DAVID G. McCAA, a citizen of the United States, residing in Palo Alto, county of Santa Clara, State of California, have invented new and useful Improvements in Signaling Methods and Apparatus, of which the following is a specification.

My invention relates to a method of and apparatus for receiving signals represented by electro-radiant energy or high frequency oscillations in radio or carrier wave conductor systems.

In accordance with my invention, the preferably sustained or undamped high frequency energy representing the signals operates in conjunction with locally produced high frequency oscillations of the same frequency to produce great changes in amplitude and therefore more easily readable or recognizable signals, the changes in amplitude being effected by periodically, and at preferably suitable audible note-producing frequency, reversing the co-action of the received and locally produced energies.

In accordance with my invention, without the production of beats, an audible signal-representing note is produced, the frequency or pitch of the note being independent of the frequencies of the received and locally produced energies and is dependent upon the frequency of reversal of the co-action between the received and locally produced energies.

My invention resides in the hereinafter described method and apparatus.

For an illustration of some of the forms my apparatus may take, and for an understanding of my method, reference may be had to the accompanying drawing, in which:

Fig. 1 is a diagrammatic view of receiving apparatus embodying my invention and illustrative of a mode of practicing my method.

Fig. 2 is a fragmentary diagrammatic view of a modification.

Fig. 3 comprises graphs representing a principle of my invention.

Referring to Fig. 1. A is an antenna or other absorbing structure of a radio receiving system, or a conductor extending between transmitting and receiving stations over which high frequency oscillations representing the signals are transmitted.

Between the structure A and the earth,

counter-capacity or return conductor E, are connected the loading or tuning inductance L, the primary P of an oscillation transformer, and the variable condenser C. Inductively related to the primary P is the secondary S, in whose circuit are the variable condenser C¹ and the primary P¹ of an oscillation transformer whose secondary S¹ is connected in circuit with the variable tuning condenser C² and alternately with the oscillation transformer primaries P² and P³ through the medium of the commutator or rotary pole changer structure D comprising circumferentially spaced conducting contacts or segments s successively engaging the brush b connected to one terminal of the secondary S¹. Alternate segments s are connected to the slip ring a, and the intervening alternate segments s are connected to the second slip ring c. Upon the slip rings a and c bear brushes connected, respectively, with the primaries P² and P³.

Inductively related to the primaries P² and P³ is the secondary S², one of whose terminals is connected to the grid g of a thermionic device comprising the bulb V, evacuated to any suitable degree, as well understood in the art, and containing in addition to the grid g the cathode or filament f and the anode w. The cathode f is connected to a point between the inductance coils L¹ and L² disposed, respectively, in the grid and anode circuits, and forming a coupling between those circuits. A variable condenser C³ is connected across the windings S² and L¹. In the anode circuit is the source of current or battery B and the telephone T, which, it will be understood, can be replaced by the primary of a transformer or other means for coupling the anode circuit to the grid circuit of a thermionic amplifier, it being understood that the number of amplifiers may be made anything suitable or desirable. Connected across the battery B and telephone T is a variable condenser C⁴.

The operation is as follows: Sustained or undamped oscillations, representing the signals, exist in the path in which is connected the primary P, which path may be attuned thereto. The circuit S, C¹, P¹ is attuned to the frequency of the oscillations, as is also the circuit S¹, C², P² or P³.

Simultaneously there are produced by the

thermionic device V and its associated circuits high frequency oscillations whose frequency is made equal to the frequency of the received energy, which frequency is above 5 audibility or supersonic. Unless the pole changer or reversing commutator D is in operation, no sound will be heard in the telephone T. If, however, the commutator D is rotated, the energy of the received oscillations is impressed alternately through primaries P and P³ upon the circuit of the secondary S². The primaries P² and P³ are so wound or connected that they influence the secondary S² in opposite senses, whereby 10 when the primary P², for example, is in circuit with S¹ and C², the received oscillations and the locally produced oscillations are within such phase relation, as indicated at the left of Fig. 3, that their algebraic sum 15 will be such that their combined amplitude is greater than the amplitude of either the received energy or locally produced energy alone; and when the primary P³ is in circuit with S¹ and C², the received oscillations and 20 the locally produced oscillations co-act in opposite sense, as indicated at the right of Fig. 3, with the result that their sum or the resultant amplitude is less than the normal amplitude. Or differently viewed, the received energy affects the potential of the 25 grid g cumulatively when the primary P², for example, is in circuit, and differentially when the transformer P³ is in circuit.

Accordingly, the uni-directional component of the current in the anode circuit of the valve V is periodically increased and decreased by the action of the commutator D, with the result that there is heard a pure note in the telephone or other instrument T, 30 the pitch or frequency of the note being dependent entirely upon the speed of rotation of the commutator D, that is, dependent entirely upon the rate of change of the circuit connections as regards P², P³, or either of 35 them. And the note or pitch of the sound in the telephone T is not dependent upon the frequency of the received energy nor upon the frequency of the locally produced 40 oscillations.

If the frequency of the received oscillations differs from the frequency of the locally produced oscillations, beats will be 45 set up, the beat frequency being equal to the difference between the frequencies of the received and locally produced energies. In such case, with the commutator D in operation, the pure note or tone produced when the frequencies of the received and locally produced energies are equal is no longer 55 pure, but is more or less ragged or irregular.

While it is preferred that the local oscillations are produced by a thermionic oscillator as described in connection with Fig. 1, it will be understood that my invention may 60 be attained by other arrangements, one of

which is indicated in Fig. 2, wherein the primaries P² and P³, controlled by a commutator, etc., as in Fig. 1, are related to the secondary S², as described in connection with Fig. 1. In circuit with the secondary S² is 70 the variable condenser C⁵ and the secondary S³ of an oscillation transformer whose primary P⁴ is in circuit with the condenser C⁶ and the generator or source G of alternating current or oscillations whose frequency is 75 made equal to that of the received energy. In a circuit in shunt to the condenser C⁵ is connected any suitable detector, as a rectifying crystal or other detector R in circuit with the telephone or other instrument T, 80 the latter shunted by a condenser C⁷.

Here again the action is the same as described in connection with Fig. 1, the primaries P² and P³ alternately coming into co-operation with the secondaries S² and 85 S³ causing alternate cumulative and differential co-actions between the received and locally produced oscillations, with resultant pure tone or note in the telephone T, the frequency of the note depending solely upon 90 the rate of rotation of the commutator, as D.

In the arrangements of both Figs. 1 and 2, with the commutator D at rest, and only one of the primaries P² or P³ in circuit with S¹ and C², the effect upon the instrument T 95 will be simply the ordinary effect of simple detector action. However, with the commutator D in rotation, the increased changes in amplitude above described are effected, and simultaneously a note of desired pitch 100 is attained.

The rate of rotation of the commutator D may be made anything suitable or desirable, but is preferably such as to produce a note in the telephone T of the order of 500, 1000 105 or more vibrations per second.

What I claim is:

1. The method of receiving high frequency oscillations, which consists in locally generating oscillations of frequency equal to the 110 frequency of the received oscillations, periodically changing the co-action of the received and locally produced oscillations, and subjecting a translating instrument to the resultant of the received and locally produced oscillations.

2. The method of receiving high frequency oscillations, which consists in locally generating oscillations of frequency equal to the 120 frequency of the received oscillations, periodically at audible frequency changing the co-action of the received and locally produced oscillations, and subjecting a translating instrument to the resultant of the received and locally produced oscillations.

3. The method of receiving high frequency oscillations, which consists in locally generating oscillations of frequency equal to the frequency of the received oscillations, periodically reversing the co-action of the re- 130

ceived and locally produced oscillations, and subjecting a translating instrument to the resultant of the received and locally produced oscillations.

5. The method of receiving high frequency oscillations, which consists in locally generating oscillations of frequency equal to the frequency of the received oscillations, periodically at audible frequency reversing the 10 co-action of the received and locally produced oscillations, and subjecting a translating instrument to the resultant of the received and locally produced oscillations.

5. Receiving apparatus comprising a wave responsive device, a signaling instrument controlled thereby, a local source of oscillations having a frequency equal to the frequency of the received oscillations, and means periodically changing the co-action of 20 the received oscillations with the locally produced oscillations.

6. Receiving apparatus comprising a wave responsive device, a signaling instrument controlled thereby, a local source of oscillations having a frequency equal to the frequency of the received oscillations, and means periodically at audible frequency changing the co-action of the received oscillations with the locally produced oscillations. 30

7. Receiving apparatus comprising a wave responsive device, a signaling instrument controlled thereby, a local source of oscillations having a frequency equal to the frequency of the received oscillations, a circuit traversed by the received oscillations, and a switch periodically changing the sense of influence of the oscillations in said circuit upon said wave responsive device. 35

8. Receiving apparatus comprising a wave responsive device, a signaling instrument controlled thereby, a local source of oscillations having a frequency equal to the frequency of the received oscillations, a circuit 40 traversed by the received oscillations, and a switch periodically reversing the sense of influence of the oscillations in said circuit upon said wave responsive device.

9. Receiving apparatus comprising a circuit 50 traversed by received oscillations, a pair of primary windings, periodically operating switching mechanism for bringing said primaries alternately into operative relation with said circuit, a secondary circuit 55 coupled to said primaries, means for producing in said secondary circuit oscillations of a frequency equal to the frequency of the received oscillations, and a signal translating instrument controlled by said secondary circuit. 60

10. Radio receiving apparatus comprising an absorbing path, a closed circuit coupled to said path, a second circuit coupled to said circuit, a pair of primaries, switching means

for bringing said primaries alternately into 65 co-operative relation with said second circuit, a secondary circuit coupled to said primaries, a source of oscillations of frequency equal to the frequency of the received oscillations, and a signaling instrument controlled by said secondary circuit. 70

11. Receiving apparatus comprising a circuit traversed by received oscillations, a thermionic oscillator, a signal translating instrument controlled thereby, and switching 75 means periodically reversing the relation of said circuit to said oscillator.

12. The method which comprises causing interaction between electrical oscillations, periodically changing the interaction between 80 said oscillations, and translating the resultant of the periodically changed interaction between said oscillations.

13. The method which comprises causing interaction between electrical oscillations, 85 periodically reversing the sense of the interaction between said oscillations, and translating the resultant of the periodically changed interaction between said oscillations.

14. The method of receiving high frequency oscillations, which comprises locally generating oscillations and causing them to interact with the received oscillations, periodically changing the sense of interaction between 90 said oscillations, and translating the 95 resultant of the periodically changed interaction between said oscillations.

15. The method of receiving high frequency oscillations, which consists in locally generating oscillations, subjecting a translating instrument to the locally generated and received oscillations, and periodically changing the sense of combination of said 100 locally generated and received oscillations.

16. The method of receiving high frequency oscillations, which consists in locally generating oscillations, subjecting a translating instrument to the locally generated and received oscillations, and periodically changing at audible frequency the sense of 110 combination of said locally generated and received oscillations.

17. The combination with a plurality of sources of oscillations of the same frequency, of a translating instrument, means for combining said oscillations in their effect upon said instrument, and means for periodically changing at audible frequency the sense of 115 combination of said oscillations.

18. The combination with a plurality of 120 sources of oscillations, of a translating instrument, means for combining said oscillations in their effect upon said instrument, and means for periodically changing the sense of combination of said oscillations.

19. The combination with a thermionic oscillator comprising an anode, cathode and control electrode, of a second source of os-

cillations controlling the potential of said control electrode, and means periodically changing the sense of control by said second source of oscillations of the potential of said control electrode.

20. The combination with a thermionic oscillator comprising an anode, cathode and control electrode, of a second source of oscillations of the same frequency controlling the potential of said control electrode, and means periodically changing at audible frequency the sense of control by said second source of oscillations of the potential of said control electrode.

15 21. Receiving apparatus comprising a thermionic oscillator comprising an anode, cathode and control electrode, a signal-translating instrument controlled by said thermionic device, means effecting control of said control electrode by the received energy, and means for periodically changing the sense of control of said control electrode by the received energy.

22. Receiving apparatus comprising a thermionic oscillator comprising an anode, cathode and control electrode for producing oscillations whose frequency is equal to the frequency of the received energy, a signal-translating instrument controlled by said 30 thermionic device, means effecting control of said control electrode by the received energy, and means for periodically changing at audi-

ble frequency the sense of control of said control electrode by the received energy.

23. Receiving apparatus comprising a closed circuit including inductance and capacity attuned to the received energy, means for delivering received energy to said circuit, a local source of oscillations, means periodically effecting interaction between the locally produced oscillations and oscillatory energy withdrawn from said closed circuit, and a signaling instrument responsive to the periodic interaction of the received energy with said locally produced oscillations.

24. Receiving apparatus comprising a closed circuit including inductance and capacity attuned to the received energy, means for delivering received energy to said circuit, a local source of oscillations having a frequency equal to the frequency of the received energy, means periodically effecting at audible frequency interaction between the locally produced oscillations and oscillatory energy withdrawn from said closed circuit, and a signaling instrument responsive to the periodic interaction of the received energy with said locally produced oscillations.

In testimony whereof I have hereunto affixed my signature this 14th day of May, 1921.

DAVID G. McCAA.
